BRACE FOR BOXED PRODUCE LOADS

Joseph N. Adams, Orange, Calif., assignor to California Fruit Growers Exchange, Los Angeles, Calif., a corporation of California

Application July 11, 1944, Serial No. 544,380

4 Claims. (Cl. 105—369)

1

This invention relates in general to improved methods and means for preparing unit loads of boxed or crated fruits or vegetables. The invention further relates to methods and means for loading railroad cars with boxed or crated produce in a manner adapted to maintain the rigidity and stability of the load during transportation.

As those familiar with the loading of boxed produce know, it is extremely difficult to prepare a load in a manner adequate to maintain the load in position during a haul of any length without serious shifting during transit. As a consequence, for example, in the loading of railroad cars with boxed produce, complex bracing systems are installed either during the loading of the car or after the car has been loaded in order to give the load satisfactory stability and to prevent breakage of the containers and damage to the perishables being transported.

During normal times, satisfactory loading of boxed produce to prevent shifting and breakage was accomplished by several different methods. However, under the stress of emergency conditions, it has become necessary to devise loads which increase the amount of produce carried, so that the methods of bracing the load heretofore used are, for the most part, inadequate and not adaptable to the heavier loads.

Before disclosing this invention in detail, it is believed desirable to verify the exact significance of several terms for those who may not be completely familiar with the nomenclature used in connection with loading of boxed produce in refrigerator cars, and particularly citrus fruit. The term "stack" as used in this art is applied to the group of boxes placed in one line transversely across the width of a railroad car. A stack may be composed of one or more "layers" of boxes. The layer of boxes resting on the floor of the car is the first layer. Additional layers placed on top of the first layer are designated as the "second layer," "third layer," etc. The top layer, especially when the individual boxes are horizontal, may sometimes be spoken of as the "deck layer." The "rows" of boxes are those boxes extending in a line the length of the car, the rows being parallel to the side wall. This terminology is intended to be observed throughout this application. Ordinarily the "brake end" of the car is used to begin numbering the stacks, so that the stack placed against the brake end of the car is called the first stack. The rows are ordinarily numbered beginning with the first row on the left as one faces the brake end of the

2

car. In accordance with the above nomenclature, it becomes possible therefore to locate any box within the car by defining its position with reference to the stack, layer, and row.

When loading refrigerator cars with boxed citrus fruit, as for example oranges, it has been customary in the past to tier the boxes two-high on end, in stacks seven boxes wide. Thirty-three such two-layer stacks ordinarily made a full load of 462 boxes. In order to comply with regulations requiring heavier loads, it has been proposed to add a third layer of boxes standing on end. The difficulties of loading and adequately bracing such a load to prevent excessive breakage and damage to the contents during loading and transit made it seem to some to be economically unsound to continue its use. However, since it has been necessary to transport heavier loads than the former two-layer load, the cars are still loaded with a third layer but the boxes making up this third layer are now placed on their bottoms instead of on end as first suggested. For a time the boxes of the third layer were placed end to end longitudinally of the car, that is with the individual boxes parallel to the walls, and for the full length of the car. It was soon found, however, that the boxes could not stand the tremendous shock sometimes imparted to them when the car was started or stopped enroute. Also adequate bracing of this load presented so many problems that this type of load is now little used. Experience shows that the difficulty encountered with the third layer loads results from the fact that the higher the boxes are loaded in the car, the more susceptible they are to transverse movement and longitudinal shock. Great stress and strain is placed on the load in general as well as the individual boxes from the starting and stopping of the cars in transit. To minimize the effect of this shock, it was found desirable to orient the containers so that their greatest strength would be opposed to the line of greatest shock. In this connection a so-called deck layer or deck load was used, comprising three boxes placed transversely end to end across the top of each stack. By so doing, the ends and center boards of the boxes were longitudinal of the car and were thus in position to absorb the stresses and strains of starting and stopping. However, by arranging the third layer in this manner a further complication arose, namely, the bracing of the third layer to maintain it in position. The inside width of a refrigerator car averages about ninety-nine inches. Three boxes of oranges, for example,

placed laterally end to end leave an additional space or channel of about twenty to twenty-one inches. It became necessary, therefore, to develop some type of brace for this space in order to keep these boxes in line and from shifting during transit. The construction and use of a satisfactory brace in connection with this third layer or deck load comprises the principal object of this invention.

Other objects and advantages and modifications will be apparent to those skilled in the art as the description proceeds in connection with the accompanying drawing in which:

Fig. 1 is a view in perspective of an end portion of a refrigerator car loaded with boxed oranges and showing the new and novel box brace in position.

Fig. 2 is a view in perspective showing in detail the placement of the box brace with respect to the boxes being braced.

Fig. 3 is a view showing a preferred embodiment of the box brace.

Fig. 4 is an enlarged view showing a preferred form of imbedding means.

Figs. 5 and 6 are enlarged views showing modifications of the imbedding element.

Referring to the drawings in detail, and in particular to Fig. 1, the boxes of oranges 10 are stacked on end within the refrigerator car to form the first and second layers. The walls of the car are designated as 11 and the end of the car as 12. While the views in the drawing do not show the complete load, the boxes of oranges 10 are loaded on end and stacked two-high to form thirty-three stacks within the car. On top of these stacks of boxes there is placed a third or deck layer comprising three boxes placed end to end across the top of each stack. Each stack, therefore, contains seven boxes of the first layer, seven of the second, and three of the deck layer, making seventeen boxes.

As mentioned hereinbefore, three boxes of oranges placed end to end across the car leave a space of about twenty inches which is not filled. In order to maintain the third layer in position, it is necessary to brace these boxes rigidly against the walls of the car. It will be seen that in the arrangement illustrated the third layer is arranged so that two rows of boxes 10 are placed along one side of the car and one row along the opposite side of the car. Bracing or spacing means are positioned in the channel between the rows of boxes. For bracing the third layer the brace shown in detail in Fig. 3 has been found to be specially adapted and satisfactory in all respects. This brace comprises a rigid member 13 with a positioning means 14 inserted into and projecting from each end thereof. As an integral part of the positioning means 14 there is an imbedding element 15. The positioning means of the brace thereby comes into position between the adjacent boxes of the opposed boxes. The boxes in the third layer are consequently braced firmly in position and the brace itself is held in position by the imbedding element at each end thereof which becomes imbedded in the sides of the adjacent boxes as will be explained more in detail hereinafter.

In loading a refrigerator car with boxed citrus, as for example, oranges, to make a so-called "561" load, the boxes are usually trucked into the car from one side only. The doors of the car opposite the loading side are closed. The boxes of fruit are stacked on end along the end of the car to form the first and second layers of the first stack.

Then three boxes of fruit are placed bottom side down transversely across the first stack to begin the third layer. Additional boxes are then trucked into the car and the first and second layer 5 of the second stack are put in place. A brace of the type shown in Fig. 3 comprising the rigid member 13 with its two positioning means 14 is then placed in the channel remaining between the boxes of the third layer atop the first stack. 10 Then the next three boxes of fruit are placed on top of the second stack. Successive stacks are then built up in a similar manner until the space within the car is filled, except for that portion in the center opposite the car doors. Ordinarily to 15 save time, a car is loaded with boxes from both ends toward the middle. A box press or squeeze is then positioned in this space and expanded in such a known manner as to press the stacks of boxes tightly together toward the ends of the car, thereby tightening the load. After the load has 20 been sufficiently tightened, the press is removed and additional boxes and channel braces are placed in the space opposite the open doors. Where the load comprises thirty-three stacks as 25 in the case of oranges and the braces are placed so that only one brace is used for each two opposed pairs of boxes, seventeen such braces are required for complete bracing of the third layer. Obviously a brace could be positioned for each 30 adjacent pair of boxes if desired.

The brace disclosed and illustrated in the drawings and particularly in Fig. 3 may be made in accordance with the following description, although it is to be understood that many modifications in type and kind of materials used in its construction may be made without departing from the general principles set forth. For example, I choose to construct the rigid member 13 of wood. A block having the dimensions of 2 by 3 by 20 inches forms a satisfactorily rigid member. The positioning means 14 is made desirably of metal and may be inserted in the block so as to leave about two inches projecting therefrom to form a satisfactory positioning means. The imbedding element of the positioning means may be larger in size than the shaft thereof in order that it may become firmly imbedded in the sides of the boxes when the load is tightened with the car squeeze in accordance with the description hereinabove set forth. Having the imbedding element pressed into the sides of the boxes assists materially in maintaining the brace in position and prevents displacement of the brace by jumping or buckling. In some cases it may be desirable to use only the positioning means in the absence of an imbedding element whereupon the positioning means itself may become imbedded in the sides of the boxes.

It should be understood that not infrequently 60 there is a strong tendency for elements of the load to undergo considerable shifting. Thus the ability of my brace to maintain itself in position, and not move or jump out of place, is a very important advantage. For, once boxes become free to move about, they will quickly be 65 destroyed.

In Figs. 5 and 6 there are disclosed modifications of the imbedding element. These are indicated by the numbers 16 and 17 respectively. 70 The length of the shaft of the positioning means is a matter of convenience but it should be adequate to insure a firm hold of the rigid member 13 and yet project sufficiently beyond the end of the member to insure that it will act to position the brace. The size and shape of the im-

bedding element may be varied as desired and necessary.

The size of the rigid member 13 is also one of convenience, although it should be of such size as to give good bracing qualities. While I have mentioned blocks of wood having dimensions of about 2 by 3, heavier blocks, as 2 by 4's or even 4 by 4's or lighter blocks such as 1 by 3's could be used. Materials other than wood of course come within the scope of the invention as, for example, various metals. When metals are used, the imbedding means should preferably be brazed or welded to the ends of the rigid member. It is obvious also that under some circumstances it may be desirable to use a modification of the hereinabove disclosed brace in which a positioning member and imbedding element project from one end only of the rigid member.

Having thus described my invention in such full, clear, concise, and exact language as to enable others skilled in the art to make and use the same I claim as my invention and desire to secure by Letters Patent the following:

1. A box brace adapted to be placed between the ends of two opposed pairs of boxes in a load in such a manner as to rigidly space apart said two opposed pairs of boxes comprising a rigid one piece spacing member of sufficient length to bear upon the ends of the two opposed pairs of boxes in the load, a one piece projection positioned in and extending from each end of said member, said projection being adapted to be inserted between the adjacent boxes of said pairs of boxes in such a manner that a portion of the end of the rigid spacing member will bear upon the end of each of the adjacent boxes of the pair, said projection having a laterally extending portion adapted to pierce and become imbedded in the adjacent sides of said adjacent boxes.

2. A box brace adapted to be placed between the ends of opposed boxes in a load in such a manner as to rigidly space apart said opposed boxes comprising a rigid spacing member of sufficient length to bear upon the ends of the opposed boxes in the load, means projecting from each end of said member, said means being adapted to be inserted between adjacent pairs of

said boxes and to become imbedded in the adjacent boxes of said adjacent pairs.

3. For use in stabilizing boxed produce loads, a spacer unit comprising a member adapted to be placed between and in engagement with the ends of oppositely positioned spaced pairs of boxes and at each side of the interengaging sides of the boxes in each pair, and a rigid one piece projection carried by and extending beyond said member and receivable between interengaging vertically extending sides of the boxes of one of said spaced pairs of boxes to prevent horizontal shifting of the brace relative to the boxes, said projection having an integral lateral portion adapted to pierce and become imbedded in the outer surface of one of the interengaging box sides to hold the spacer unit against upward displacement.

4. A box brace adapted to be placed between the ends of two opposed pairs of boxes in a load in such a manner as to rigidly space apart said two opposed pairs of boxes comprising a rigid spacing member of sufficient length to bear upon the ends of the two opposed pairs of boxes in the load, projecting means secured in and extending from each end of said member, each of said means being provided with a perimetrical imbedding element, said projecting means adapted to be inserted between the sides of adjacent boxes of said pairs of boxes in such manner that the imbedding element will pierce and become imbedded therein and a portion of the end of the rigid spacing member will bear upon the end of each of the adjacent boxes of the pair.
